UNITED STATES PATENT OFFICE.

GEORGE R. HENRY, OF DENVER, COLORADO.

FLYING-MACHINE.

1,339,336.

Specification of Letters Patent.

Patented May 4, 1920.

Application filed December 22, 1917. Serial No. 208,364.

To all whom it may concern:

Be it known that I, GEORGE R. HENRY, citizen of the United States, residing in the city and county of Denver and State of Colorado, have invented certain new and useful Improvements in Flying-Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in flying machines of the aeroplane class, my object being to minimize danger and at the same time increase the power, whereby great weight may be carried and greater speed attained.

20 My improved construction provides a new type of aeroplane which is designed to fly or move through the air in a direction lengthwise of the machine, thereby making it practicable to employ one or more driving propellers mounted on each side of the plane and elevating propellers attached at or near the front and rear ends respectively of the machine.

25 The type, shape and construction of the cover, wings, drop-walls, and the position of the body of the frame work, together with that of the machinery or operating mechanism, arranged as they are in relation to the air-bearing surface, make it practicable to carry out the idea of maintaining the machine when in the air in the proper or upright position, thereby minimizing danger in aviation. Where my improved machine is

30 employed, if the operator should lose control of the machinery or if through accident the power should cease to be available, necessitating descending, my improved machine would move downwardly in the upright position. In my improvement the wings or cover over the frame work have the concaved side down, while the drop-walls on the frame divide the currents of air, whereby they are equally distributed over the entire

35 air bearing surface, whereby these currents are caused to move to the rear end of the machine making their influence most effective. Hence, the air currents produced by the propellers on the opposite sides of the machine not only exert a propelling or driv-

ing force by their rearward travel, but also exert a supporting or lifting force underneath the curved planes or covering of the machine, which covering is located immediately above the upper edges of the drop walls and extends on both sides thereof.

40 My improved flying machine includes a frame work built in elongated form, the width, height and length being properly proportioned. The width and height of the body of the frame work may be the same or approximately the same, while the length may be from six to ten times the width.

45 Having briefly outlined my improvement, I will proceed to describe the same in detail, reference being made to the accompanying drawing in which is illustrated an embodiment thereof. In this drawing:

50 Figure 1 is a side elevation of my improved flying machine.

55 Fig. 2 is an end elevation or a view looking toward the right from line 2—2, Fig. 1.

60 Fig. 3 is a fragmentary top plan view of the operating mechanism taken on the line 3—3, Fig. 1 looking downwardly.

65 Fig. 4 is a top plan view of the flying machine, or a view taken on the line 4—4, Fig. 1 looking downwardly.

70 Fig. 5 is an elevation taken on the line 5—5, Fig. 1 looking toward the right, the parts being shown on a larger scale.

75 Fig. 6 is a section taken on the line 6—6, Fig. 5, viewed in the direction of the arrows, the parts being shown on a larger scale.

80 Fig. 7 is a fragmentary view of one of the propellers, the same being shown on a larger scale than in Fig. 5.

85 Fig. 8 is a section taken on the line 8—8, Fig. 3, the parts being shown on a much larger scale.

90 Fig. 9 is a section taken on the line 9—9, Fig. 3, the parts being shown on a much larger scale.

95 Fig. 10 is a vertical longitudinal section taken on the line 10—10 Fig. 4 viewed in the direction of the arrows.

100 Fig. 11 is a perspective view of the stabilizing top wing.

105 The same reference characters indicate the same parts in all the views.

Let the numeral 5 designate the frame work of the structure which is composed of a number of vertically disposed side bars 6, constituting two rows of such bars, the bars of each row being longitudinally spaced and

the two rows being transversely spaced forming a rigid body or frame work which is provided with central depending bars 7 carrying supporting wheels 8, there being 5 two bars 7 spaced transversely and arranged at the opposite extremities of the machine and suitably spaced, the wheels 9, as illustrated in the drawing being raised somewhat above the wheels 8 which are centrally located between the wheels 9.

The frame work of the machine is provided with a covering 10 which is secured to the top of the frame bars 6 and is curved, its lower surface being concave and extending 15 beyond the frame work on opposite sides, as shown at 12. This covering may be of any suitable construction, being preferably composed of a light skeleton frame work covered with canvas or other suitable material. The covering as well as the frame work 5 is relatively long as compared with its width. This covering is connected with the frame work by guy-wires or cables 13 arranged in any suitable manner in order 20 to give the necessary rigidity to the covering of the frame work of the structure.

The machine is further provided with relatively short depending side walls 14 which are secured to the vertically disposed 30 side bars 6, the lower edge of the side walls extending approximately to the level of the lower free edges of the side members 12 of the covering. These side walls space the air currents and compel these currents 35 to be confined between the top covering and the side walls, whereby the currents are caused to extend rearwardly for propelling purposes and also to act upon the covering parts 12 to perform to some degree the lifting 40 function.

The machine is provided on opposite sides with longitudinally disposed shafts 15 which are suitably spaced and equipped with any desired number of propellers 16 45 which may be of any suitable construction. The shafts 15 are journaled in transversely arranged bars 17, which as illustrated in the drawing extend considerably below the side members 14 and the covering parts 12, 50 which extend laterally beyond the frame work, as heretofore explained.

As illustrated in the drawing, there are three propellers 16 arranged on each shaft 15, though it must be understood that a 55 greater number of propellers may be employed or a smaller number but not less than two if the machine is to be properly stabilized.

These propellers are operated from an 60 engine or motor 18 having an operating shaft 19 carrying a gear 20 meshing with a gear 21 fast on a second shaft 22. The shafts 15 are operated by connecting pulleys 23 fast thereon with other pulleys 24 65 which are normally loose on the respective

shafts 19 and 22, said connection being made by means of belts 28. Furthermore, each shaft 15 is equipped with a relatively small pulley 25 which is connected by means of a belt 26 with a larger pulley 27. By virtue 70 of this construction, each shaft 15 may have a high or low speed as may be desired. As heretofore indicated, both the pulleys 24 and the pulleys 27 on the two shafts 19 and 22 are normally loose on said shafts. 75 Each of these shafts is provided with a clutch member 29 splined thereon and composed of two parts 30 adapted to interlock with either the pulley 24 or the pulley 27, the clutch member being shiftable through 80 the medium of a lever 31 fulcrumed on the frame, as shown at 32 and manually operable, as will be readily understood. When the clutch member is shifted to engage the pulley 24 of either shaft, the propeller shaft 85 15 is operated at low speed, while when the clutch is shifted to interlock with the pulley 27, the propeller shaft is operated at high speed, since the pulleys 27 are considerably larger than the pulleys 25. It should 90 be explained that one of the propeller shafts 15 may be operated at high speed and the other at low speed. This enables the operator to turn the machine by controlling the propellers, since if the propeller shaft 95 on one side is rotated at a higher speed than the corresponding shaft on the other side, the machine will be turned toward the side whose propeller shaft is operated at relatively low speed as will be readily understood.

Attention is called to the fact that the machine is provided with a number of vertically disposed propeller shafts 33 and 34, the shaft 33 being located near the rear end 105 of the machine and the shaft 34 near the forward end. These shafts are journaled in the frame work of the structure and are independently operable through the medium of horizontally disposed shafts 35 and 36 110 which are also journaled in the frame work above the shafts 15. The shaft 35 is operably connected with the shaft 33 through the medium of beveled gears 36^a and 37, the gear 36^a being fast on the shaft 35 and 115 the gear 37 fast on the shaft 33. The shaft 35 is operably connected with the shaft 19, through the medium of a belt 38 connected with a pulley 39 which is fast on the shaft 35 with a loose pulley 40 normally loose 120 on the shaft 19. The pulley 40 while normally loose on the shaft 19, as just explained, is adapted to be interlocked with the shaft through the medium of a clutch 41 splined on the shaft 19 and shiftable through the 125 medium of a lever 42 fulcrumed at 43, the lever being operably connected, as shown at 44, with a collar 45 having a circumferential tongue 46 adapted to engage the corresponding groove 47. Again, the shaft 36 130

is provided with a beveled gear 48 which meshes with a similar gear 49 fast on the vertical shaft 34. The shaft 36 is operated through the medium of a belt 50 which connects a pulley 51 normally loose on the shaft 22 with a pulley 52 fast on the shaft 36. When it is desired to operate the shaft 34, a clutch 53 which is splined on the shaft 22 is shifted into engagement with the 10 normally loose pulley 51, whereby the latter is operated to actuate the shaft 36 and the shaft 34 through the medium of the gears 48 and 49.

Each of the shafts 33 and 34 extends upwardly through the curved covering 10, its upper extremity being equipped with a lifting or elevating propeller 54, which also may be used to hover in the air and to make a very slow descent. When the shafts 33 and 34 are operated, the propellers 54 are actuated to lift the machine vertically. In starting the machine the forward propeller 54 may be first set in motion until the forward end of the machine is tilted sufficiently to cause it to rise at a suitable inclination. The rear propeller 54 may then be set in motion, in which event both propellers 54 will serve to perform the lifting or elevating function and the machine may 30 then be kept in an inclined position if desired with both of the lifting propellers in motion, or after the machine is started, the operation of the lifting propellers may be discontinued and the machine controlled entirely by the driving propellers 16 arranged on opposite sides of the machine, as heretofore explained.

Supported above the longitudinally disposed concavo-convex wing, plane or covering 10, is a transversely disposed stabilizing warped wing or plane 55 which is supported in the center by uprights 56 extending upwardly from the side bars 13 of the main frame 5. This stabilizing plane or wing 55 is warped to produce a central depression 57, the two opposite sides of the wing being bowed upwardly between their extremities, as shown at 58, while the opposite ends of the wing are bowed upwardly 50 between their extremities, as shown at 59. This warped auxiliary wing aids as heretofore stated, in maintaining the machine in a state of equilibrium.

From the foregoing description the use and operation of my improved flying machine will be readily understood. When the machine is resting upon the ground preparatory to beginning a flight, it will rest upon the rear pair of wheels 9 and the 60 central pair of wheels 8, thus tilting the forward extremity, or that at the left in Fig. 1, upwardly. The propellers 16 on both sides of the machine are then set in motion by the propeller adjustment of 65 the clutches 29, whereby the shafts 15 are

operated at either high or low speed, depending on whether the pulleys 23 or 25 are connected in operative relation with the shafts 19 and 22. Which ever speed these shafts are running at, the machine will be 70 driven forwardly and upwardly, the direction of flight coinciding with the longitudinal dimension of the machine or of the wing or plane 10 whose concave surface is lowermost, as heretofore explained. The 75 two lifting propellers may be set in motion one at a time or both at the same time as desired. If only one is put in motion in the first instance, it should preferably be the forward propeller since this motion will 80 have a tendency to tilt the forward extremity of the machine upwardly as is required in commencing a flight. The rear propeller may then be set in motion, that is to say, after the machine is properly tilted; 85 in which event both of the propellers 54 will serve to perform the elevating or lifting function. Each of the driving propellers has a beveled face 60 at its outer extremity which has a tendency to throw the 90 air upwardly, while the other face of the propeller is driving the air rearwardly on opposite sides of the machine. This upward tendency of the air, together with a certain degree of compression due to the 95 longitudinally flowing air currents developed by the driving propellers 16 and confined by the drop walls 14 and the outer side portions of the main wing, will exercise a lifting tendency on the downwardly 100 bent or curved portions 12 of the main plane or wing. In this way the driving propellers also serve to perform a lifting function.

When it is desired to turn the machine, 105 the propellers on the opposite side from that toward which the machine is to turn, will be operated at a high speed while the propellers on the inner side will be operated at low speed.

This will compel the side where the high speed propellers are located to travel so to speak, faster than the opposite side, thus causing the machine to turn in the desired direction.

Attention is called to the fact that in making a descent the concavo-convex plane or wing will perform the function of a parachute, the parts of the machine being arranged to bring the gravity center of the 120 machine below the center of the main wing or plane. By virtue of this peculiar construction of the main wing or plane, the machine may be allowed to descend in a vertical direction in case the engine should become disabled, since the wing having its concave surface lowermost and extending on opposite sides of the main central frame work together with the drop walls 14 will resist the too rapid downward movement of 125 130

the machine. In making a descent, when the machine is in use the lifting propellers 54 may be used to steady the downward movement of the machine in a vertical direction, the propellers 54 being operated just fast enough to retard any tendency of the machine to move downwardly more rapidly than is desirable.

Of course, when making a descent when 10 the engine and all parts of the machine are operative and capable of performing their proper functions, the machine may be caused to glide in an inclined direction in the manner usual with flying machines of 15 the aeroplane type. My machine, however, has the advantage over others so far as I am aware, of being able to make a vertical descent either with or without the use of the lifting propellers.

20 The top plane 57 which is disposed transversely to the direction of flight and cross-wise of the main wing or plane 10 facilitates the maintaining of the machine in a state of equilibrium at all times. Attention 25 is called to the fact that the plane 55 in addition to the supports 56 is further connected with the frame work of the machine and with the parts 12 of the main wing, by means of a series of guy-wires or cables 61.

30 Having thus described my invention, what I claim is:

1. A flying machine including a frame work whose length is several times its width and which is longitudinally disposed to the 35 direction of flight, a main wing applied to the top of said frame work and having its corresponding dimensions similarly proportioned and coincidentally disposed, the said wing extending laterally on both sides of the 40 frame work, and a stabilizing wing whose length is greater than its width, the said wing being mounted above the main wing and having its length disposed at right angles to the direction of flight, said stabilizing 45 wing being spaced upwardly from the top of the main wing and having a central depression, the side and end portions of the wing being bowed upwardly between their extremities.

50 2. A flying machine including a frame work longitudinally disposed to the direction of flight, a single rigid main wing plane applied to said frame and having its under 55 face concaved longitudinally and provided with drop walls forming in connection with the wing separated longitudinally extending air channels along the under face of the wing, and a plurality of propellers on each side of the machine located one in the rear 60 of another and below and within the limits of certain of said air channels, said propellers being adapted to direct air currents upwardly against the under face of said wing and into said channels.

65 3. A flying machine including a single

relatively stationary main wing plane disposed longitudinally to the direction of flight and having its under face concaved longitudinally and provided with drop walls which form in connection with the wing 70 plane separated longitudinally extending air channels along the under face of the wing plane, and a plurality of propellers on each side of the machine located one in the rear of another, and below and within the limits 75 of certain of said air channels, said propellers having their blade faces constructed to direct currents of air upwardly against the under face of said wing plane and into certain of said channels and to direct currents of air directly rearwardly.

4. A flying machine, including a main wing whose length is several times greater than its width, its length being longitudinally disposed with respect to the direction of flight, and a stabilizing wing whose length is greater than its width, the said stabilizing wing being spaced from the main wing and having its length disposed at right angles to the direction of flight, 90 said stabilizing wing having a central depression, the side and end portions of the wing being bowed vertically between their extremities.

5. In combination in a flying machine, a frame work whose length is several times its width and which is longitudinally disposed to the direction of flight, a single main wing plane applied to the top of said frame work and having its corresponding 100 dimensions similarly proportioned and coincidentally disposed, the said wing extending laterally on both sides of the frame work, having its under surface concaved longitudinally and provided with spaced 105 drop walls forming in connection with the wing separate fixed air channels extending longitudinally along the under face of said wing, a plurality of propellers on each side of the machine located one in the rear of 110 another and below and within the limits of said air channels, said propellers having their blade faces constructed so as to direct currents of air upwardly against the under face of said wing and into certain of said 115 channels and to direct currents of air directly rearward, a motor, and means connected therewith for operating said propellers.

6. In combination in a flying machine, a main wing plane whose length is greater than its width and is disposed lengthwise with respect to the direction of flight, said plane having its under face concaved lengthwise, drop walls extending downwardly from said wing plane and to the level of the longitudinal edges thereof, forming in connection therewith fixed air channels extending longitudinally thereof, a stabilizing wing whose ends and side por- 130

tions bow upwardly having a central depression, and whose length is greater than its width, said stabilizing wing being disposed above the central portion of the main wing and transversely thereof, propellers horizontally arranged on both sides of said frame work and centrally below certain of said air channels, said propellers being constructed to direct air currents upwardly and 5 rearwardly, elevating propellers arranged above the said main wing plane and near each end thereof to lift the machine, to hover in the air and to stabilize movement of the machine, a motor and operative connections between the motor and all of the 10 propellers, all the parts of the machine being arranged to place the gravity center of the combined weight of said parts below the central portion of the said main wing 15 plane, the main wing plane thereby constituting a parachute.

7: A flying machine, including a navigable parachute comprising a main wing plane, said wing plane being greater in 20 length than in width and having its under

face concaved lengthwise, drop walls extending downwardly from the wing, and lengthwise thereof, forming in connection therewith outer air channels and a median air channel, a framework whose length is 25 several times its width, attached to said main wing plane and positioned below said median air channel, a stabilizing wing whose length is greater than its width arranged above the main wing plane and 30 transversely thereof, said stabilizing wing having a central depression and having its end side portions bowed vertically, propellers arranged on each side of the framework and below said outer air channels to 35 drive the machine horizontally, other propellers arranged on top of said framework and near each end thereof, said propellers being operated to lift or lower the machine horizontally to glide or hover in air, a 40 motor, and operative connections between the motor and all the propellers.

In testimony whereof I affix my signature.

GEORGE R. HENRY.
